Des. 213,950

Patented Apr. 29, 1969

213,950

FLINT-DISPENSING CAP

Edgar Strelow, Raboisen 101, Hamburg 1, Germany

Filed Nov. 9, 1967, Ser. No. 9,338

Term of patent 14 years

Int. Cl. D9—99

U.S. Cl. D9—275

FIGURE 1 is a top perspective view of my flint dispensing cap embodying my new design,

FIG. 2 is a top plan view thereof,

FIG. 3 is a front elevational view thereof,

FIG. 4 is a side elevational view thereof.

I claim:

The ornamental design for a flint-dispensing cap, substantially as shown.
